UNITED STATES PATENT OFFICE

102,648

DESIGN FOR A V-TYPE MARQUEE

Morton L. Clark, Lima, Ohio, assignor to The Artkraft Sign Company, Lima, Ohio, a corporation of Ohio

Application September 12, 1936, Serial No. 64,823

Term of patent 7 years

To all whom it may concern:

Be it known that I, Morton L. Clark, a citizen of the United States, residing at Lima, in the county of Allen and State of Ohio, have invented a new, original, and ornamental Design for a V-Type Marquee, of which the following is a specification, reference being made to the drawings, forming a part hereof,

Fig. 1 represents a perspective;
Fig. 2 represents a front elevation; and
Fig. 3 represents an underside view, looking up, of my new marquee.

I claim:
The ornamental design of a V-type marquee as shown.

M. L. CLARK.
